UNITED STATES PATENT OFFICE.

WILSON B. MILLER, OF INDIANAPOLIS, INDIANA.

FARM-GATE.

SPECIFICATION forming part of Letters Patent No. 286,053, dated October 2, 1883.

Application filed June 7, 1883. (No model.)

To all whom it may concern:

Be it known that I, WILSON B. MILLER, a citizen of the United States, residing at Indianapolis, in the county of Marion and State of Indiana, have invented new and useful Improvements in Farm-Gates, of which the following is a specification.

This invention relates to swinging farm-gates in which the hinge end is mounted upon a bottom pivot-pin between two posts, and the swing or latch end suspended by diagonal wires from the tops of the said posts to effect the self-closing of the gate; and the particular point of improvement consists of a perforated I-shaped iron piece for the suspension-wires, combined with the slotted top bar of the gate, said slot being formed longitudinally in said bar, and the said iron piece being perforated at both ends to receive the separate suspension-wires, whereby to take up the sag of the gate by adjusting the iron piece within the slot as may be required. The cross-bar at the top of the supporting-posts, which braces said posts and forms the bearing for the suspension-wires, is formed on its outer side with a series of grooves or notches in which the separate suspending-wires are adjusted to equalize the draw on the gate and cause it to close itself with more or less force.

Referring to the accompanying drawings, Figure 1 represents an elevation of a gate embodying my invention; Fig. 2, an elevation of the gate in its open position; Fig. 3, a top view of the gate as closed; Fig. 4, a cross-section of the top slotted bar, showing the I-shaped perforated iron piece for the separate suspension-wires; and Fig. 5 shows a top view of the wires crossing each other over the notched top bar of the posts, and Fig. 6 shows the latch-lock.

The gate is made of the usual or any appropriate construction, having the longitudinal bars *a*, connected by vertical posts *bb*, and diagonal braces *a'*, and is mounted and swung upon a bottom pivot-pin, *c*, between posts *B B*, placed diagonally to each other in relation to the line of the gate when closed, and between which the pivot end of the gate is supported.

C is the latch-post, having the catches *D* for the latch. The separate suspension-wires *dd* pass around a cross-brace, *F*, at the top of the posts *B B*, thence down on each side of the

gate, and are secured at the bottom thereof to a metal plate, *e*, pivoted on each side of the gate. These wires are preferably double on each side of the gate, and pass from the pivot-plate *e* through perforations *ii* in the projecting ends of a fulcrum iron piece, *G*, seated and confined by end arms, *gg*, in a slot, *H*, in the top rail, *a'*, of the gate, and are secured in notches *n* around the diagonal brace *F* at the top of the posts *B B*. This diagonal end brace, *F*, is secured against the sides of the posts, and in the notches *n* on its rear side the wires are adjusted to change the angle of the suspension-wires with reference to the line of the gate, and thereby cause the same to close automatically. The perforated I-shaped piece or fulcrum *G* is arranged to be set in the slot *H*, formed through the top rail of the gate and extending in a longitudinal direction therewith. The object of this metal piece *G* is to take up the sag in the gate consequent upon the settling of the posts and lengthening of the wires. This is accomplished by moving said piece *G* forward in the slot, whereby the wires are caused to make a sharper angle, and thereby raise the swinging end of the gate and hold it in position free of the ground. The arms of the piece *G* hold it endwise within the slot at top and bottom, and the wires are confined within its perforations.

I is the latch, pivoted near its lower end, and connected to the pivot-plate *e* by a rod or short wire, *m*, in such manner that the pulling action of the suspension-wires in opening the gate will tend to keep the latch always in position to be closed. At the top of the gate, adjacent to the handle of the latch, is arranged a lock-block, *J*, hinged to the top of bar *b*, and fitting into a recess, *s*, formed in the top rail, as shown in Fig. 2, to lock the latch when the gate is closed. At the front portion of this hinged piece *J* is formed a slot, *s'*, into which the latch fits when said hinged piece is down in position to lock the latch.

On the inner side of the gate, at its bottom portion, is arranged a prop, *L*, pivoted to one of the lower bars of the gate, which prop, when brought down in position with its end against the ground, will hold the gate in its open position, as shown in Fig. 2. In the example shown two separate wires on each side of the gate are employed, and are preferable; but a

single wire may be used. It is important to notice that in using two separate and distinct wires they cross each other in extending above the gate and around the top notched bar, as shown in Fig. 5, and that they so pass and are confined in separate notches, and that the strain upon the wires is resisted by the firm and solid position of the cross-bar against the rear sides of the posts. This arrangement of the wires equalizes the draw on the gate as it is opened, and equalizes the strain upon the wires. The form of the iron piece G, with the perforations in each end, adapts it to be confined within the slot without fastenings, and to receive the wires.

I have stated that the diagonal brace F is secured against the sides of the posts, and it will be understood that the said brace-bar is placed against the posts next to the fence, and that the tops of the posts are cut away diagonally to form shoulders or seats for the brace-bar, and the latter is nailed down upon said seats and to the cut-away sides at the top part of the posts above the seats. In other words, the tops of the posts are notched obliquely to receive the oblique brace-bar, so that the strain upon the latter is supported directly by the posts.

Referring to the vertical bars *b b* of the gate, it will be seen that they, like the braces, are secured on each side of the longitudinal bars *a*, and that the pivot *I'* of the latch *I* is secured in a cleat, *b'*, and to the end of the longitudinal bar, through which said pivot also passes. The slot *s'* for the upper end of the latch *I*, at the top of the gate, is formed between the top rail and a cleat, *s'*, fastened to the latch side of the gate, to the top of the front bar *b* and

the brace *a'*, and to the end of the top rail, and the recess *s* for the hinged block *J* is formed in the top edges of this cleat *s'* and the upper rail, *a'*, so that the hinged locking-block *J* fits into this recess over the slot.

I claim—

1. In a swinging gate pivoted at its lower inner end, the combination, with the top rail, *a'*, of the gate, having the slot *H*, of the perforated I-shaped piece, *G*, fitted within and adapted to be adjusted in said slot, and the suspension wire or wires secured to the bottom front end of the gate, and passing through the perforations in said piece, and around a diagonal bar, *F*, at the top of the posts, having notches *n*, as and for the purpose set forth. 45

2. The combination, in a swinging gate pivoted at its lower inner end, of the posts *B B*, connected at the top by the cross-bar *F*, having notches *n* on its rear side, with the gate having its top bar formed with the slot *H*, the perforated I-shaped piece *G*, the suspension wires *d d*, the pivoted plates *e*, and the latch, all constructed and arranged as shown and described. 50

3. In a swinging gate, the combination, with the top rail of the gate, having a recess, *s*, at its top front end, of the lock-block *J*, hinged to the top rail, having a slotted end and fitting within the recess in the rail, and the latch *I*, as and for the purpose set forth. 60

In testimony whereof I have hereunto set my hand in the presence of two subscribing witnesses.

WILSON B. MILLER.
